CLAIM

The ornamental design for a ponytail accommodating headwear, as shown and described.

DESCRIPTION

FIG. 1 is a front elevational view of a ponytail accommodating headwear showing our new design.

FIG. 2 is a back elevational view of a ponytail accommodating headwear showing our new design.

FIG. 3 is a right elevational view of a ponytail accommodating headwear showing our new design.

FIG. 4 is a left elevational view of a ponytail accommodating headwear showing our new design.

FIG. 5 is a top plan view of a ponytail accommodating headwear showing our new design.

FIG. 6 is a bottom plan view of a ponytail accommodating headwear showing our new design.

FIG. 7 is an upper left back perspective view of a ponytail accommodating headwear showing our new design in an alternate position.

FIG. 8 is a lower back perspective view of a ponytail accommodating headwear showing our new design in an alternate position; and,

FIG. 9 is an upper right back perspective view of a ponytail accommodating headwear showing our new design in an alternate position.

The broken lines on claimed surfaces depict stitching and form no part of the claim.

1 Claim, 9 Drawing Sheets
